CAR TOP LUGGAGE CARRIER

Donald G. Hart, R.R. 1, Geneseo, Ill. 61254

Filed Nov. 8, 1973, Ser. No. 413,876

Term of patent 14 years

Int. Cl. D12—16

U.S. Cl. D12—157

FIG. 1

FIG. 2

FIG. 3

FIG. 5

FIG. 4

FIG. 1 is a front elevational view of a car top luggage carrier showing my new design;

FIG. 2 is an end elevational view thereof, with the opposite end being identical therewith;

FIG. 3 is a top plan view thereof;

FIG. 4 is a rear elevational view thereof; and

FIG. 5 is a bottom plan view thereof.

I claim:

The ornamental design of a car top luggage carrier, substantially as shown.
